TENSION FOR LOOM SHUTTLES

Richard G. Turner, Worcester, Mass., assignor to
Crompton & Knowles Loom Works, Worcester,
Mass., a corporation of Massachusetts

Application November 6, 1948, Serial No. 58,735

8 Claims. (Cl. 139—217)

1

This invention relates to improvements in weft tensions for loom shuttles and it is the general object of the invention to provide a tension so constructed as to minimize the likelihood of cutting the weft which passes through the tension.

A form of shuttle which has gone into extensive use for the weaving of fine wefts employs a pair of tension pads which are pushed toward each other and against the weft by small springs. These pads may take the form of vertical members mounted for a limited amount of motion relatively to the shuttle and constructed with vertical edges which in the past have been substantially straight. When the shuttle is checked near the end of its flight the pads because of the manner of their mounting and because of their momentum move angularly with respect to each other and pinch the weft thread sufficiently to cause breakage.

It is an important object of the present invention to form the pads with part of their vertical edges cut back slightly to avoid pinching of the weft when the pads move angularly with respect to each other.

With these and other objects in view which will appear as the description proceeds, the invention resides in the combination and arrangement of parts hereinafter described and set forth.

In the accompanying drawings, wherein two forms of the invention are shown,

Fig. 1 is a plan view of one end of the shuttle having the preferred form of the invention applied thereto,

Fig. 2 is an enlarged transverse vertical section on line 2—2 of Fig. 1,

Fig. 3 is a detailed horizontal section on line 3—3, Fig. 2,

Fig. 4 shows the pads in horizontal section and indicates two different positions which they assume during running of the shuttle,

Fig. 5 is a perspective view of one of the pads,

Fig. 6 is a view similar to Fig. 4, but showing the modified form of the invention, and

Fig. 7 is a side elevation looking in the direction of arrow 7, Fig. 6.

Referring particularly to Fig. 1, the shuttle S carries a bobbin B the weft W of which unwinds from the bobbin and passes through a thread passage 10 formed in the thresher block 11 when the shuttle is in flight.

The thresher block has mounted therein two vertically extending tension pads 13 and 14 which are located respectively in front of and behind the weft thread. The lower end of each pad is provided with an opening 15 which fits loosely

2

on a support pin 16 fixed to the thresher block 11. The upper end of each pad is formed with a lateral extension or finger 17 which fits into an opening 18 in the thresher block. The finger 17 does not fully occupy the opening 18 and permits some freedom of motion of the upper end of the pad.

Each pad is urged toward the other by a light compression spring 20 backed up by a screw 21 threaded into the block 11, and each pad is provided with a substantially flat vertical weft engaging surface 22 along which the thread moves horizontally or longitudinally of the shuttle when the latter is in flight.

As will be understood from Fig. 2 the extension or finger 17 of each pad is located at one side of a vertical line passing along the corresponding flat surface 22, and when the shuttle is checked near the end of its flight the finger 17 by reason of its momentum produces a slight rocking or angular movement of the pad. This rocking occurs with respect to both pads and the latter momentarily move from the full line position to the dotted line position shown in Fig.

25 4. In the past these pads have had continuous vertical straight edges adjacent to each other, and when the pads pivot on each other around their vertical edges as axes the edges pinch the weft and weaken it so that it is likely to break.

20 The matter thus far described is of usual construction and operates in the usual manner, the springs 20 determining the amount of frictional contact which the pads have with the weft thread and the pads being mounted freely so they can move angularly when the shuttle is checked in its flight.

In carrying the present invention into effect provision is made to prevent the angular movement of the pads from cutting the weft. This result is accomplished by removing a part of the vertical straight edges heretofore used. The drawings show two means for carrying the invention into effect, but the invention is not necessarily limited to the two forms shown in Figs. 4 and 6.

45 Referring particularly to Figs. 4 and 5, and considering one side of one of the pads, it will be seen that pad 13 has an upper straight primary edge 30 which is more or less in vertical alignment with a lower straight primary edge 31. These two edges or parts of pad 13 are spaced from each other by a low area or portion 32 which may be produced by chamfering the edge of the pad between the edges 30 and 31. The effect 50 of this chamfering is to produce a secondary edge

33 for the pad which is spaced from a line joining the edges 30 and 31 in the direction of the length of travel of the thread. Both sides of both pads are formed as already described, but the invention will operate if only one pad has its edges chamfered.

While the shuttle is in flight the two pads will be in the positions shown in full lines in Fig. 4, but when the shuttle is checked, as by engagement with the shuttle binder, the guide fingers 17 due to their momentum tend to move in the direction of shuttle travel faster than the shuttle is traveling. This causes the pads to rock to the dotted line positions shown in Fig. 4. During this rocking the pads pivot on themselves by engagement of their upper and lower primary edges 30 and 31, respectively, but during this pivoting the secondary edge 33 of the chamfer of one pad moves away from the similar edge 33 of the other pad, thereby defining a small open space 38 through which the thread can move, and there is no opportunity for the thread to be pinched or broken.

In the modified form of the invention shown in Figs. 6 and 7 the primary vertical edges 40 and 41 correspond to the vertical edges 30 and 31 of the preferred form, but the sides of the pad are cut back as at 42 to provide secondary edges 43 similar to edges 33 of the preferred form. The operation of the modified form is substantially the same as that of the preferred form, as will be understood from Fig. 6, where the full position of the two pads is that existing while the shuttle is in full flight and wherein the dotted lines indicate the rocked position of the pads when the shuttle is checked. In the modified form the edges 43 which determine one of the horizontal limits of the surface which engages the thread moves away from the corresponding edge 43 of the other pad and a small opening is defined for the thread.

The pads are free to move angularly with respect to each other whenever the shuttle is checked, whether it be moving to the right or left across the loom and both vertical edges of each pad will be modified as set forth hereinbefore so that whether the pads rock from the full to the dotted line position shown in Fig. 4, or whether they rock in the opposite direction due to the fact that the shuttle is moving reversely, they will nevertheless separate to open a small gap through which the weft can pass without being pinched.

From the foregoing it will be seen that the invention sets forth a tension pad for a loom shuttle constructed in such manner that angular movement of the pads with respect to each other and about an axis determined by mutual engagement of parts of the pads will effect a separation of those parts of the pad across which the weft passes. This result can be accomplished either by chamfering the edges of the pads as in the preferred form of the invention, or by removal of a small part of the sides of the pads as in the modified form of the invention.

Having thus described the invention it will be seen that changes and modifications of the foregoing specific disclosure may be made without departing from the spirit and scope of the invention.

What is claimed as new is:

1. In weft tension mechanism for a loom shuttle having a threader block with a thread passage therethrough, a pair of vertically extending tension pads mounted on the block, said pads having adjacent vertical edges around which the

pads have angular movements when the shuttle is checked in its flight, and said pads having flat weft engaging faces which terminate out of vertical alignment with said edges and move apart to define a space for the thread when the pads have said angular movements.

2. In weft tension mechanism for a loom shuttle having a threader block with a thread passage therethrough, a pair of vertically extending tension pads mounted on the block, said pads having upper and lower engaging parts around which said pads have angular movements when the shuttle is checked near the end of its travel, said pads having portions thereof between said parts which move away from each other to define a space for passage of the weft when the pads have said angular movements.

3. In weft tension mechanism for a loom shuttle having a threader block with a thread passage therethrough, a pair of vertically extending tension pads mounted on the block, at least one of said pads having upper and lower parts engaging the other pad and having an angular movement around said parts when the shuttle is checked in its flight, said one pad having a portion thereof between said parts which moves away from the other pad to define a space for the weft when said one pad has said angular movements.

30 4. In weft tension mechanism for a loom shuttle having a threader block with a thread passage therethrough, a pair of vertically extending tension pads mounted on the block, each pad having vertically spaced vertical edges adjacent to similar edges on the other pad and the pads having angular movements around said edges when the shuttle is checked near the end of its flight, each pad having a flat thread engaging surface and the pads being so formed that the parts thereof engaging the weft move apart to define a space for the thread when the pads have said angular movement.

5. In weft tension mechanism for a loom shuttle having a threader block with a thread passage therethrough, a pair of vertically extending tension pads mounted on the block, said pads having adjacent vertical edges and having weft engaging faces which terminate at points spaced longitudinally of the shuttle from said edges, said pads having angular movements about said edges when the shuttle is checked in its flight and the faces of the pads moving apart to define a space for the weft when the pads have said angular movements.

55 6. In weft tension mechanism for a loom shuttle having a threader block with a thread passage therethrough, a pair of vertically extending tension pads mounted on the block, at least one of said pads having a primary edge below the path of travel of the thread through the threader block and having a weft engaging face terminating in a secondary edge above said primary edge and spaced from the latter longitudinally of the shuttle, said one pad having an angular movement around said primary edge when the shuttle is checked in its flight and the secondary edge moving away from the weft to avoid injury thereto.

7. In weft tension mechanism for a loom shuttle having a threader block with a thread passage therethrough, a pair of vertically extending tension pads mounted on the block, each pad having a primary edge below the path of travel of the thread through the threader block and having a vertically extending weft engaging face

terminating in a secondary edge above the primary edge and out of vertical alignment with said edge and spaced from the latter in the direction of travel of weft through said passage, said pads having angular movements about the edges thereof when the shuttle is checked in its flight and said secondary edges moving in directions away from the weft to avoid abrasion thereof.

8. In a loom shuttle of the automatic threading type having a threading block mounted in one end thereof which threading block is provided with a thread channel through which the filling yarn passes from the bobbin to the outlet, and spring pressed tension members loosely mounted

in the threading block and between which the filling yarn passes, said tension members having their coacting faces shaped to provide relatively wide portions at the top and bottom and a relatively narrow portion therebetween.
